Primary Examiner — Richelle G Shelton

(74) Attorney, Agent, or Firm — Holtz, Holtz & Volek PC

(57) **CLAIM**

The ornamental design for a display screen with icon, as shown and described.

DESCRIPTION

FIG. 1 is a front view of a display screen with icon showing our new design; and,

FIG. 2 is a front detail view thereof.

The broken lines represent a display screen and forms no part of the claimed design.
